UNITED STATES PATENT OFFICE.

JOHN HENRY NYENHUIS, OF CHICAGO, ILLINOIS.

PROPELLER FOR VEHICLES.

1,305,401.

Specification of Letters Patent. Patented June 3, 1919.

Application filed February 5, 1917. Serial No. 146,552.

To all whom it may concern:

Be it known that I, JOHN HENRY NYENHUIS, a citizen of the United States, residing in Chicago, in the county of Cook and State 5 of Illinois, have invented a new and useful Improvement in Propellers for Vehicles, of which the following is a specification.

This invention relates in general to propellers adapted to engage the ground to advance a vehicle provided therewith and it 10 has more particular reference to farm tractors and the like.

A principal object of this invention is the provision of a tractor or other vehicle in 15 which a propeller is incorporated; and of well balanced construction; and having its component parts constructed and arranged to develop maximum propelling force upon the ground through the utilization of minimum power.

My invention contemplates the provision of a propeller from the surface of which will extend blades adapted to enter into soft and yielding ground. Where these blades 25 extend out from the propeller in fixed position with respect to the carrying wheel or drum, the portion of the blades successively disposed beneath the surface of the ground must be given a backward swinging action, 30 this for the reason that the surface of the ground contains a temporary axis for such blades, the part of the tractor located above the ground moving ahead and the part below consequently swinging backwardly. 35 This causes displacement of a large part of the subjacent earth at an expenditure of considerable power, particularly where the tractor is heavy and therefore packing the dirt as it rolls over it. An object of the invention is to provide a propeller, the blades 40 of which will not be thus affected in angularity and can consequently be projected directly into the ground and removed along their entering path of travel causing merely 45 an incision instead of earth displacement.

Other objects and advantages of the invention are the provision of such mechanism which will be readily adjustable, likely to require little repair and of simple and economic construction.

Other objects and advantages of the invention will be apparent as it is better understood from the following description when considered in connection with the accompanying drawing illustrating a preferred embodiment thereof.

Referring to the drawings,

Figure 1 is a side elevation of a tractor provided with a propeller embodying my present invention;

60

Fig. 2 is a top plan view of the same;

Fig. 3 is an enlarged detail sectional view of the propeller; and

Fig. 4 is an enlarged front view, certain of the parts being broken away and shown 65 in sections to disclose particular features of construction.

On the drawings, reference character 11 indicates generally the main or tractor frame. The showing of this frame on the 70 drawing is little more than diagrammatic, its particular construction being unimportant to the consideration of the present invention. It carries, however, a pair of front wheels 12 and rear wheels 13 mounted on 75 suitable axles 14 and 15 having bearings 16 and 17 beneath the frame. In order that the tractor may be properly balanced the motor, generally indicated at 18, is mounted at one side and the propeller, generally indicated 80 at 19, on the other. These parts preferably do not differ appreciably in weight and each is disposed upon a side of the longitudinal center of the main or tractor frame. A main power shaft 21 extends across the frame and 85 is mounted in suitable bearing brackets 22. This power shaft, through chain drives 23, transmits power to the rear wheels 13 which are the wheels used to drive the tractor in travel over hard or firm ground and under 90 normal conditions. The motor in the present instance is a gas engine connected through a clutch 24 to a gear 25 on a stud shaft 26, said stud shaft carrying also a gear 29 meshing with a gear 30, upon the main 95 power shaft. The propeller already mentioned is provided to drive the tractor through soft ground and when the driving wheels 13 prove insufficient. This propeller is mounted in a propeller frame, which propeller frame is pivotally mounted upon the main power shaft 21. It comprises two side arms 31, each secured at an end upon the main power shaft and connected by a cross member or brace 32 and adjacent the ends, 100 having bearings upon the main power shaft, and at the other end by an angle member 33. The side arms 31 extend downwardly at an angle from the main power shaft 21 and then horizontally toward the front of the 110 tractor, the horizontal portion carrying the active propelling parts. Two bearing brack-

ets 34 are formed beneath the propeller frame and at opposite sides in which brackets are mounted two crank arms 35 and 36, these two crank arms having a journal 37 in 5 the brackets, the outer end of which journal is connected with a yoke 38, the purpose of which will be later described. The other ends of the crank arms form bearings for the propeller axis 39 upon which is mounted 10 what may be termed a propeller wheel, this wheel, in the present instance, comprising a pair of multiple arm spiders 41 which carry projectable blades 42. The two spiders are fixed to a common central sleeve 43 having 15 flanges 44 engaging the spiders so that both spiders turn together.

The crank arm 36 provides a bearing for a regulating disk 45, which disk is continuously driven by a chain drive 46 from the 20 main power shaft 21 through two sprockets, one 47 on the main power shaft and the other 48 fixed on the disk. The disk is provided with a plurality of bearing apertures 49 in number equal to the number of radial 25 arms of each spider. Each blade is pivotally mounted in a pair of appropriately arranged spider arms and at one side is provided with a crank arm 51 extending into an aperture in the disk. Each blade 42 is 30 fixed to its arm 51 and consists of side arms 52 and 53, preferably of sturdy angle iron construction. The side arms 53, *i. e.*, the arms at one side are rigidly fixed upon journals 54 extending into the bearings in 35 the ends of the arms of the adjacent spider, and the arms 52, *i. e.*, the arms at the other side are fixedly secured upon the ends 55 of the crank arms 51 which ends are journaled in the bearings in the ends of the arms of 40 the other spider. As will be noted from viewing Fig. 3 the crank arms 51 are disposed angularly with respect to the side arms 52 and 53. Since the propeller wheel is eccentrically arranged with respect to the 45 disk, rotation of the disk will impart rotation to the propeller wheel and cause the blades to be projected throughout a part only of the travel of the wheel. The rotation of these two members causes the propeller arms to maintain a fixed parallelism 50 with respect to each other, the angularity of which is determined by the shifting of the disk with respect to the axis of the wheel. This shifting is accomplished by 55 moving the yoke 38 already mentioned and this yoke terminates in an upwardly extending manipulating lever or handle 56 having a tooth 57 engageable in a locking rack segment 58 upon the propeller frame.

60 The construction of the parts is preferably such that the blades are presented to the ground in true edgewise fashion so that they need merely cut into the ground, their angularity with respect thereto being maintained by the disk. This arrangement causes

the blades to enter and leave on the same path of travel.

The shifting of the lever or handle 56 is attended by two results, namely, a vertical adjustment of the spiders or propeller wheel 70 and an alteration of the point of projection of the blades. Comparing Figs. 3 and 4 it will be noted that if the manipulating lever or handle 56 be moved away from the shaft 21, the arms 35 and 36 will be elevated, lifting the wheel and shifting also all of the propeller blades causing a projection thereof at a point above the ground. The lower end of the propeller frame is supported also from the main frame by a pin or rod 61 75 pivoted at one end to an arm 62 of a bell crank shifting lever 63 and extending through the angle member 33. A spring 64 renders this a yielding connection and permits the propeller frame to be lifted should the blades in their action encounter any obstruction in their operation. The lever 63 may be set in any position by engagement with a locking rack segment 65 as shown in 80 Fig. 1. A clutch 71 may be inserted, if desired, between the main power shaft 21 and the sprocket 47 thereon.

It will be manifest from the foregoing that the propeller blades enter and leave the ground without displacing any appreciable part of the earth, and the structure 95 is simple, sturdy and efficient.

It will also be manifest from the foregoing that the propeller is located in line with a front and rear wheel at one side of the main tractor frame and that the central part of the frame need be provided with no parts extending down toward the ground thus permitting the tractor to pass along and above a row of corn or other growing 100 plants without mashing the same. Furthermore, such an arrangement permits the hooking on of a series of plows, cultivators or other implements behind the tractor and preferably in line with the side of the tractor provided with the propeller so that the drive is direct, and the tractor need not run upon the ground already plowed or cultivated in the immediate preceding travel 105 across the field.

It will be manifest also that the blades described and projectable from the propeller wheel or drum may have any desired shape.

It is thought that the invention and many of its attendant advantages will be understood from the foregoing description, and it will be apparent that various changes may be made in the form, construction and arrangement of the parts without departing from the spirit and scope of the invention 110 or sacrificing any of its material advantages, the form hereinbefore described being merely a preferred embodiment thereof.

I claim:

1. In a tractor or the like, the combina- 130

- tion of a frame, a wheel support therefor, a propeller having driving blades projectable into the ground, said blades having a reciprocatory movement into and out of the ground along the same line of movement and without appreciably disturbing the material of the ground. 5
2. In a tractor or the like, the combination of a frame, a wheel support therefor, a propeller having a rolling plane on or above the surface of the ground and having a blade projectable therebefore and into the ground, said blade having a reciprocatory movement into and out of the ground along the same line of movement and without appreciably disturbing the material of the ground. 10
3. In a tractor or the like a combination of a frame, a wheel support therefor, a wheel carried by said frame, driving blades mounted on the wheel projectable into the ground to propel the vehicle, means of maintaining the same angularity of the blades with respect to the ground. 15
4. In a tractor or the like a combination of a frame, a wheel support therefor, a wheel carried by said frame and driving propeller blades carried by the wheel and projecting at a predetermined point in the travel of the wheel and into the ground, and entering and leaving the ground at the same line of travel and means for altering the point of projection. 20
5. In a tractor or the like the combination of a frame, a wheel support therefor, a wheel carried by said frame, propeller blades pivotally mounted in said wheel, each having an arm, a disk to which said arm is pivotally connected, said disk having an eccentric movement and means for shifting the eccentricity of said wheel and disk. 25
6. In a tractor or the like the combination of a frame, a wheel support therefor, a wheel carried by said frame and having driving
- blades arranged in permanent parallelism with each other and means for altering the inclination of said blades. 45
7. In a tractor or the like, the combination of a tractor frame, a motor carried by the same on one side, of its longitudinal axis, a propeller frame mounted upon the other side of its said longitudinal axis, and a propeller wheel carried in said propeller frame, whereby said motor and propeller frame distribute their several loads at the sides of a central axis. 50
8. In a tractor or the like, the combination of a tractor frame, power driven wheels for the same adapted to drive the tractor under normal conditions, and a propeller located at a side and in line with a front and corresponding rear wheel, said tractor being unobstructed centrally and longitudinally to permit the tractor to pass over a row of corn with its ground engaging parts disposed along opposite sides thereof. 55
9. In a tractor or the like, the combination of a tractor frame having a front and rear wheel in substantial alinement at a side of said frame, a propeller located midway of said frame and in substantial alinement with said front and rear wheels, and means on the other side of the central axis of the tractor for balancing the load and weight of said tractor. 60
10. In a tractor or the like, the combination of a tractor frame having a front and rear wheel in substantial alinement at the side of the frame and a propeller wheel located midway the length of the frame and in substantial alinement with said front and rear wheel. 65
